METHOD OF SHIPPING SHEET BARS AND
ANALOGOUS METAL PIECESAlva H. Moon, Middletown, Ohio, assignor to The
American Rolling Mill Company, Middletown,
Ohio, a corporation of OhioApplication November 21, 1930
Serial No. 497,210

5 Claims. (Cl. 206—60)

The primary object of my invention is the provision of an improved way of shipping metal pieces, such as short sheet bars; and although my invention is not confined to the shipping of articles in a package, which articles are held together in what is essentially a plurality of horizontally disposed stacks, yet my invention is particularly adapted to the handling of assemblies of pieces of sheet metal, bar metal, or other articles, whether metallic or not, in which, in any horizontal direction, there are a plurality of separate pieces in any given layer.

It has been the practice to ship sheet metal, for example, in a package in which the sheets are stacked one on another and are held in an integral package and against horizontal displacement with reference to each other by means encircling the package in both horizontal directions. This method is not applicable to the shipping of sheet bars with the same degree of success for the reason that in such packages, as ordinarily constructed, those encircling members which are parallel to the longer dimension of the bars, or the like articles, and which therefore engage the bars at their ends, do not engage the ends of all of the bars, and therefore the bars are liable to displacement with reference to each other by a movement in line with their longer dimension. It might be possible to encircle a package of bars with enough bands or other tying members to engage the ends of all of the bars, but this is both expensive and inconvenient. Consequently, in many shipments of sheet bars it has been the practice to encircle the package with lengthwise bands only, the package being an oblong assembly of sheet bars in a plurality of stacks, the longer dimension of the sheet bars extending along the shorter dimension of the package. This construction left the sheet bars unprotected at their ends against a lengthwise sliding movement and impact. In a co-pending application, Serial No. 491,761, filed October 28, 1930, I have described a construction of package and a method of shipping articles of this class, as well as other articles, in which an artificially produced configuration of the package is caused to tighten the lengthwise bands, whereby the sheet bars in the package are more tightly clamped together. I have found that this produced a superior type of package.

A specific object of my present invention, however, is to provide a construction of package in which the articles are more positively assembled in unit relationship and held against such relative movement in the package as would tend to

destroy the unitary character thereof. An object of my invention is to gain the desired result in a construction which is at once simple and inexpensive but completely effective to the desired end. Still another object of my invention is to gain the desired result in a package in which the encircling members are not subjected to unusual or undue strain.

These and other objects which will be set forth hereinafter or will be apparent to one skilled in the art upon reading these specifications, I accomplish by that certain construction and arrangement of parts of which I shall now describe a preferred embodiment, reference being had to the drawing, in which the figure is a perspective view of a finished package made in accordance with my invention.

Briefly stated, my invention comprises the assembling of sheet bars or similar articles in a series of piles of such size and so disposed as to form a package of the required dimensions. The package is bound by lengthwise encircling tying members such, for example, as bands or strips of wire. A waster sheet or similar article is employed at the sides of the package to engage the ends of the bars, and is held by transverse encircling bands. It is not necessary that the waster sheet contact the ends of all of the bars, nor that it be co-extensive with the sides of the package. It is sufficient if it contact, cover, or protect from longitudinal movement the ends of the sheet bars in substantially the upper half, or a little more, of the package. The lowermost articles have relatively a very little tendency to shift lengthwise, both because the strain is greater in the upper part of the package by reason of the longer leverage, and also because the frictional resistance to movement of the bars is enormously increased in the lower part of the package by reason of the relatively great weight of the superposed layers. Through the use of the side members aforesaid, I find that I can effectively prevent endwise motion of the bars in the package, although I ordinarily use but one or two transverse tying members in the package, which members alone would not be adequate to prevent the said movement, because they would not contact or cover the ends of all of the bars.

In the figure, shown as disposed in the corner of a gondola car, I have indicated an assemblage of sheet bars 1, stacked in a plurality of piles 1a, and etc. In the embodiment shown there are 6 tiers or piles, and the bars are laid with their longest dimension crosswise of the bundle. The bundle rests upon skids 6, which may be of two

by four lumber, and I have shown a pair of lengthwise encircling tying members 2, which in this embodiment are wires tied or twisted together in the usual commercial manner. Where 5 these wires contact the corners of the package formed of the several stacks 10, and etc., I have shown corner pieces 3 of bent sheet or plate metal. The wires 2 may rest upon the skids 6 beneath the package, or not, as desired. I may employ in this 10 type of package a pyramidal method of stacking, whereby I finish off the bundle on top with one or more layers 7 and 8 of sheet bars, which are progressively less in length than the length of the package, whereby the binding action of the longitudinal ties 2 is effectively increased upon the 15 central portion of the package. I may also place a longitudinally disposed sheet bar 9 under each of the lengthwise ties on the top of the package.

I have shown a waster sheet or like article 5 20 disposed on the side portions of my package. In order to assist in holding it in position, particularly during the assembling of the package, I bend over the upper portion of the sheet as at 5a, forming a flange, and I dispose this flange in engagement over the top of my assembly. As hereinabove explained, the dimensions of the waster sheet 5 do not have to be co-extensive with the dimensions of the sides of my package, but may be considerably less. Nevertheless the dimensions should preferably be such as will cause 25 the waster sheet 5 to engage or cover a portion of the ends of all of the bars in the upper part of the package. I have shown in the figure a waster sheet long enough to extend partly over the ends 30 of the bars in piles 1a and 1f, and deep enough to extend downwardly a distance somewhat more than half the height of the package. As hereinabove explained, it is not necessary that the sheet cover or contact the ends of the bars in the lower 35 part of the package because such bars have a relatively negligible tendency to shift with reference to each other. It would be possible to employ, with entire satisfaction, a sheet of such dimensions as would extend to the bottom of the package or would cover the entire side thereof.

It will be observed that in my package the structure used for shipping purposes only comprises merely the skids, the lengthwise and transverse ties, the angle pieces 3, and the waster sheets 5, whereby I secure an adequately protected package with very little dunnage.

Having thus described my invention, what I claim as new and desire to secure by Letters Patent, is:—

55 1. A package of metal articles comprising a series of said articles arranged in a plurality of horizontally disposed contiguous piles, the longer dimension of said articles extending in the direction of the shorter dimension of said assemblage, 60 longitudinal tie members encircling said assemblage in the direction of its longer dimension, and lateral tie members encircling said assemblage in the direction of its shorter dimension, and means interposed between the ends of said ar-

ticles and said lateral tie members, said means adapted to extend over the ends of said articles in at least the upper half of said assemblage.

2. A package of metal articles comprising a series of said articles arranged in a plurality of 80 horizontally disposed contiguous piles, the longer dimension of said articles extending in the direction of the shorter dimension of said assemblage, longitudinal tie members encircling said assemblage in the direction of its longer dimension, and lateral tie members encircling said assemblage in the direction of its shorter dimension, and means interposed between the ends of said articles 85 in at least the upper half of said assemblage, said assemblage resting upon longitudinally disposed skids.

3. In a package, a plurality of rectangular metal articles disposed in a plurality of horizontally arranged contiguous piles, longitudinal encircling tying members about said assemblage and laterally disposed tying members about said assemblage, and sheet metal members one on either side of said assemblage at the ends of 95 said articles, said sheet metal members having a bent over flange engaging said assemblage on the top thereof, and a depending portion engaging said assemblage at said sides, said depending portion being large enough to cover the ends of a 100 substantial number of said articles in the upper part of said assemblage, said sheet metal members lying beneath said tying members.

4. In a package, a plurality of rectangular metal articles disposed in a plurality of horizontally arranged contiguous piles, longitudinal encircling tying members about said assemblage and laterally disposed tying members about said assemblage, and sheet metal members one on either side of said assemblage at the ends of 110 115 said articles, said sheet metal members having a bent over flange engaging said assemblage on the top thereof, and a depending portion engaging said assemblage at said sides, said depending portion being large enough to cover the ends of a 120 substantial number of said articles in the upper part of said assemblage, said sheet metal members lying beneath said tying members, said assemblage resting upon longitudinally disposed skids.

125 5. In a package, a plurality of metallic pieces of generally rectangular shape arranged in a number of horizontally disposed contiguous piles, sheet metal members each having a portion bent over to form a flange arranged with said flange 130 engaging over the top of said piles, the remaining portion of said sheet metal portions depending to cover the ends of said pieces in a substantial portion in not less than the upper half of said assemblage, and lateral and longitudinal tying members 135 arranged to encircle said assemblage, one set of said tying members holding said sheet metal members in place.
